John B. McHarg

UNITED STATES PATENT OFFICE.

JOHN B. McHARG, OF ROME, NEW YORK.

IMPROVEMENT IN TOY CARTRIDGE-EXPLORERS.

Specification forming part of Letters Patent No. 159,107, dated January 26, 1875; application filed October 28, 1874.

To all whom it may concern:

Be it known that I, JOHN B. McHARG, of Rome, Oneida county, in the State of New York, have invented an Instrument for Exploding Blank Cartridges, of which the following is a specification, reference being had to the accompanying drawing, forming part thereof.

My invention consists of a hollow metal cylinder, closed at one end, the other open, and fitted to receive a flange-headed and primed metallic cartridge, analogous to a breech-loading gun-barrel, the said cylinder having a lateral opening to permit the escape of the gas of the exploded cartridges, with a cap constructed to fit over the open end of the tube, retained in place by a spring-catch, which may engage with an annular projection on the outer surface of the cap, the inner face of the head of the cap being preferably provided with a projection for firing the cartridge, the whole being designed to be attached to the end of a cane, or to the head of an arrow.

Figure 1 is a side surface view of my invention complete, attached to the broken-off small end of a cane. Fig. 2 is a similar view of the same turned quarter round. Fig. 3 is a central sectional view of the same. Fig. 4 is a face view of the spring-catch, and Fig. 5 is a side view of the same. Fig. 6 is a central sectional view of the head of a cane, containing my invention in a modified form.

H is a metal cylinder, in the one end of which is formed a chamber to receive a metallic cartridge, B, the flange-primed head of which rests on the end of the cylinder. C is a cap, which fits over the end of the cylinder H. Across the center of the inner face of the head of the cap is preferably a rib or projection, c, which, when the cap is driven down upon the cylinder, impinges upon the head of the cartridge and fires it. Upon the outer surface of the cap may be an annular rib or projection, b, in which is cut a notch, e. D is a spring-catch secured at one end to the ferrule A. The opposite end rests upon the cap, and holds it in place on the cylinder. The cap may be liberated by either lifting the free end of the spring D, or preferably by turning the cap so that the projection d coincides with the notch e, when the cap may be put on or taken off, the projection passing through the notch. Any equivalent device

may be employed for holding the cap on the cylinder. F is a large aperture in the side of the cylinder, opening into the cartridge-chamber, through which the gas of the exploded cartridge may escape.

This cartridge-exploder is designed to be attached to the end of a cane, E, by the ferrule A, as represented in the drawings, Figs. 1, 2, and 3, or in any other suitable manner. It is also designed to be attached in like manner to the head of an arrow, to be fired at some solid object from a bow.

In place of being attached to the small end of a cane, as shown in the drawings, it may be attached to the head or knob, in which case the position of the cartridge may be reversed and inserted in the head, the open end of the cartridge inward, a proper annular shoulder being provided in the cartridge-chamber in the head of the cane, for the flange of the cartridge-head to rest upon, and an aperture made in the head for the escape of the gas.

With this modification, which is shown in Fig. 6, a shank on the end of the shaft of the cane is fitted to follow the cartridge into the cane-head, which, being forced against the cartridge, will explode it.

In a cane provided with this instrument, a cartridge may be carried for any length of time, as a cane is ordinarily used in walking, and may be exploded at pleasure by striking the cane down forcibly upon the hard ground or pavement.

When attached to an arrow, the flight of the arrow will carry it with sufficient force against a hard object to explode the cartridge.

The general design of the invention is to furnish a safe, convenient, and attractive instrument to explode blank cartridges for innocent amusement.

What I claim as my invention, and desire to secure by Letters Patent, is-

As an attachment for canes, arrows, and similar articles, a blank-cartridge exploder composed of the cylinder H, having a lateral aperture, F, and the cap C, combined to operate as and for the purpose described.

Witness my hand this 24th day of October, 1874.

JOHN B. McHARG.
